DES. 2097

Letters Patent No. 2097 Dated June 12, 1865.

Design for a Medallion or Head of Abraham Lincoln.

This schedule referred to in these Letters Patent and forming part of the same.

To all whom it may concern,

Be it known that I, James Powell, of Cincinnati, in the County of Hamilton and State of Ohio, have invented a new Design for a Medallion or Bas-Relief, of Abraham Lincoln, and I do declare the same to be correctly represented in the accompanying photographic representation thereof, which is hereby made a part of this specification.

What follows is new and deserves to secure by Letters

Patent is

The design herein represented and described for a medallion or bas-relief, of Abraham Lincoln.

Anteriorly of which invention, circumscribed and including
